GARTER GRIP

John E. Holtzclaw, Los Angeles, Calif.

Application August 30, 1938, Serial No. 227,496

5 Claims. (Cl. 241—6)

This invention relates to improvements in garter grips.

The general object of the invention is to provide a novel improved hose support.

5 A more specific object of the invention is to provide a novel garter grip which in connection with the usual garter upholds the hose adequately yet does not bind the wearer's leg.

Another object of the invention is to provide 10 a novel garter grip which allows loose adjustment of the garter thus preventing discomfort, irritation and poor circulation.

Other objects and advantages of my invention will be apparent from the following description 15 taken in connection with the accompanying drawing, wherein:

Fig. 1 is a view of a garter grip embodying the features of my invention as used with a standard garter;

20 Fig. 2 is a top plan view of the garter grip; Fig. 3 is a side elevation of the garter grip;

Fig. 4 is a section taken on line 4—4 Fig. 2;

Fig. 5 is a top plan view showing a slight modification of my invention; and

25 Fig. 6 is a section taken on line 6—6 Fig. 5.

Referring to the drawing by reference characters I have shown my invention as embodied in a garter grip which is indicated generally at 10. As shown in Fig. 1 the garter grip 10 may 30 be employed with a standard garter 11 which includes an elastic or flexible band 12 and the usual fastening device 13 which engages the hose 14.

The garter grip 10 includes a circular disk-like 35 body or base portion 15 having a concave under face 16 and a convex upper face 17 and is preferably formed of soft flexible rubber.

A strap or loop portion 18 is spaced above the base portion 15 and is integral therewith as at 19 40 and 19' forming a slot 20 adapted to accommodate the band 12 of the garter 11.

Ventilation apertures 21 which pierce the base portion 15 may be provided for affording communication to the concave under face 16.

45 The tapered lower portion 22 of a spur member 23 engages a central aperture 23' in the base portion 15 and is held therein by the resiliency of the rubber. The spur member 23 includes an intermediate flange 24 which engages the upper 50 face 17 and an upstanding point 25 which extends through an aperture 26 in the strap 18. The spur member 23 is preferably molded from a suitable plastic such as Bakelite.

In use the band 12 of the garter 11 is passed 55 through the slot 20 and is engaged by the spur

member 23. The garter 11 and the garter grip 10 are preferably placed as shown in Fig. 1, the grip 10 being positioned on the upper, outer portion of the wearer's calf. The grip 10 engages the flesh and allows loose adjustment of the 5 garter while providing ample support to the hose. It will be seen that discomfort due to tight garters is entirely eliminated by my garter grip.

In Figs. 5 and 6 I show a modification of my invention wherein the spur member 23 and aperture 26 are omitted. In the modification the body 30 is made of rubber or other suitable material and includes a strap or loop portion 31 similar to the body 15 and strap 18 previously described. The use of the modification is similar 15 to that of the main embodiment already described.

From the foregoing description it will be apparent that I have invented a novel garter grip 20 which is efficient in use and economical to manufacture.

Having thus described my invention, I claim:

1. A garter grip including a flexible disk having a concave lower face, an integral diametral strap spaced above said disk and forming a slot 25 therewith adapted to engage a garter band, ventilation holes communicating with said concave lower face, said disk having an aperture, a spur member positioned within said disk aperture, said strap having an aperture, said spur 30 extending through said aperture in said strap, said spur being adapted to engage the band of a garter.

2. In a garter, a band, a hose engaging fastener suspended from said band, a garter grip engaging said band, said garter grip including a disk having a concave lower face and having a strap spaced above said disk and forming a slot therewith receiving said band of said garter, a spur member on said disk, said strap having an 40 aperture, said spur extending through said aperture in said strap and engaging said band of said garter.

3. In a garter, a band, a hose engaging fastener suspended from said band, a garter 45 grip engaging said band, said garter grip including a resilient flexible disk having a concave lower face and having an integral diametral strap spaced above said disk and forming a slot therewith securing said band of said garter, ventilation holes communicating with said concave lower face, said disk having a central aperture, a spur member positioned within said central aperture in said disk, said strap having an aperture, said spur extending through said aperture 50 55

in said strap, said spur engaging said band of said garter.

4. A garter grip made of a single piece of rubber and including a resilient flexible limb engaging face member and a resilient flexible strap having its ends integral with said limb engaging member to form a loop adapted to engage a garter band.

5. In a garter, a band, a hose engaging fastener suspended from said band, a garter grip engaging said band, said garter grip comprising a single piece of rubber including a thin, resili-

ent, flexible disk having a concave limb engaging face and having an integral resilient strap, said strap having its ends secured to the flexible disk within the periphery of the disk and having its intermediate portion free from said disk, said strap forming a slot slidably receiving said band of the garter, the strap being resilient whereby it holds the disk in set place while permitting adjustment of the disk along the band to correct position.
